CLAIM

We claim the ornamental design for a cutting tool, as shown and described.

DESCRIPTION

FIG. 1 is a side elevation view of a toothform for a cutting tool according to one embodiment.

FIG. 2 is an enlarged side elevation view of a portion of the toothform of FIG. 1; and,

FIG. 3 is an end view of the toothform of FIG. 1.

Portions of the cutting tool shown in broken lines form no part of the claimed design. The dash-dot-dash lines represent the locations and borders of an enlarged view showing details and form no part of the claimed design.
